DESIGN FOR A LAMP

Maurice Langbaum, Brooklyn, N. Y.

Application December 4, 1936, Serial No. 66,310

Term of patent 3½ years

To all whom it may concern:

Be it known that I, Maurice Langbaum, a citizen of the United States of America, residing at Brooklyn, in the county and State of New York, have invented a new, original, and ornamental Design for a Lamp, of which the following is a specification, reference being had to the accompanying drawing, forming part thereof, wherein,

The characteristic feature of my design resides in the lamp arm, as shown.

I claim:

The ornamental design for a lamp, substantially as shown, and described.

MAURICE LANGBAUM.
